UNITED STATES PATENT OFFICE.

JOHN T. DONOVAN, SR., OF LAMPASAS, TEXAS.

ORE-SEPARATOR.

No. 921,374.

Specification of Letters Patent. Patented May 11, 1909.

Application filed July 16, 1907. Serial No. 384,083.

To all whom it may concern:

Be it known that I, JOHN T. DONOVAN, Sr., a citizen of the United States, residing at Lampasas, in the county of Lampasas and 5 State of Texas, have invented new and useful Improvements in Ore-Separators, of which the following is a specification.

This invention relates to separators or concentrators for separating or extracting 10 gold from pulverized quartz, sand or gold bearing dirt; and it has particular reference to an improved pneumatic separator for extracting or separating flake and flour gold.

The invention has for its object to provide 15 a machine of the class referred to which shall possess superior advantages in point of simplicity, durability and general efficiency; and with these and other ends in view which will readily appear as the nature of the invention is better understood, the same consists in the improved construction and novel 20 arrangement and combination of parts which will be hereinafter fully described and particularly pointed out in the claims.

25 In the accompanying drawing has been illustrated a simple and preferred form of the invention; and in said drawing the single figure represents a vertical sectional view of an apparatus constructed in accordance with 30 the invention.

The improved apparatus comprises a casing constructed with a wind trunk, which includes a vertical limb 1 adjacent to the front end of the casing, a vertical limb 2 adjacent 35 to the rear end of the casing, and an approximately horizontal portion 3 that extends longitudinally through the casing and connects the limbs 1 and 2.

4 represents a suction fan, the casing of 40 which 5 is supported adjacent to the rear end of the casing; the eye 6 of the fan casing being in communication with the lower end of the limb 2 of the wind trunk.

A trough 7 is suitably supported adjacent 45 to the lower end of the limb 1, which latter is provided near its lower end with an inlet aperture 8 and a shield 9 which constitutes a guide or hopper over which material may be guided to the inlet aperture 4 from a suitably supported shaking screen 10, which, in 50 turn, receives the material from the hopper 11.

Hingedly supported within the limb 1 of the wind trunk, near the upper rear end of 55 the latter, is a shield or deflector 12, the lower end of which has an adjusting rod 13

extending through the front wall of the limb and provided with an adjusting nut 14 whereby the shield or deflector may be adjusted within the limb 1 so as to regulate the 60 effective area of the lower portion of said limb.

The horizontal portion 3 of the wind trunk is provided with expanded portions forming 65 hoppers 15 and 16 adjacent to the front and rear ends of the casing, respectively. Suitably supported for rotation in the hopper 15 is a cylindrical screen 17; and cleats 18 are disposed to contact with said screen, and to coöperate with the latter to obstruct the 70 wind trunk or passage. An inclined deflector 19 extends from the top of the wind trunk downwardly and rearwardly into the hopper 16; and a horizontally disposed deflector 20 is arranged adjacent to the upper 75 rear edge of said hopper. The hoppers 15 and 16 are provided with outlets designated respectively 21 and 22.

The crushed or pulverized ore or sand or other material that is to be operated upon 80 is fed over the shaking screen 10 and through the aperture 8 into the lower end of the limb 1 of the wind trunk, in which suction is set up by means of the fan 4 which is driven in any convenient manner; the shield 12 85 being adjusted according to the specific gravity of material that is to be operated upon and other well known conditions. The particles of material, suspended in the air current, will presently impinge upon the 90 cylindrical screen 17, which is suitably rotated, the comparatively fine particles passing through the screen while the coarser particles are separated through the outlet 21 of the hopper 15. Within the hopper 16 95 another separation takes place, the relatively heavy and coarse particles being deflected by the deflectors 19 and 20 and separated through the outlet 22, while the flour gold, which is in the form of an impalpable 100 powder, will continue on through the limb 2 of the wind trunk and through the fan casing, being finally delivered into a dust collector which is suitably connected with said fan casing, and a portion of which is conventionally indicated at 24.

This improved separator, as will be seen, is extremely simple in construction and operation, and it has proven in practice to be thoroughly efficient for the purposes for 110 which it is provided. By means of this machine, the flake and flour gold may be ex-

tracted in a rapid and efficient manner; the machine may be driven with light expenditure of power; and the course of separation does not call for water, and is for this reason especially useful in arid localities.

Having thus fully described the invention, what is claimed as new is:—

1. In an ore separator, a wind-trunk having a horizontal limb, a V-shaped hopper in communication at its upper portion with the bottom of the limb and having an outlet at its lower reduced end, a horizontal deflector projecting forwardly from the upper rear portion of the hopper above the chamber of the latter and parallel with the plane of the limb, a second deflector arranged in rear of the vertical center of the hopper and extending at a downward and forward angle from the top wall of the limb and coöperating with the horizontal deflector to contract the limb above the upper rear portion of the hopper, and a rotary screen mounted to rotate partially within the hopper and partially within the limb between said deflectors, said screen being arranged to leave a passage between the same and the front wall of the hopper for the entrance of the coarser material which cannot pass the screen to said hopper.
2. A separator of the character described comprising a casing having a wind-trunk including vertical front and rear limbs and an upper horizontal limb communicating with the upper ends of said vertical limbs, the latter being provided respectively with

an inlet and an outlet at their lower ends, the lower end of the front wall of said front limb terminating above the lower end of the rear wall thereof, V-shaped hoppers arranged between the vertical limbs and depending from the base of the horizontal limb, each of said hoppers being provided at its lower reduced end with an outlet communicating with the underlying portion of the casing, a horizontal deflector projecting forwardly from the upper rear portion of each hopper above the rear wall of said hopper and parallel with the horizontal limb, inclined deflectors arranged in advance of said horizontal deflectors and projecting rearwardly from the upper wall of the horizontal limb at a downward angle, a screen guarding the upwardly extending duct above the forward hopper, a conical receptacle arranged at the base of the vertical inlet limb, a suction device communicating with the outlet of the vertical discharge limb, ore feeding means, and an inclined chute extending from said delivery means to a point between said conical receptacle and the lower end of the short front wall of the inlet limb and spaced from the latter to provide an intervening feed passage communicating with said limb.

In testimony whereof, I affix my signature in presence of two witnesses.

JOHN T. DONOVAN, SR.
